COMBINATION BOAT FENDER AND LIFE
RAFT

Leon R. Jenkins, Miami, Fla.

Application December 9, 1949, Serial No. 132,149

3 Claims. (Cl. 114—219)

1

This invention relates to an improvement in combination boat fenders and life rafts or life preservers.

It is an object of the present invention to provide a boat fender constructed of heavy canvas or the like formed into a tubular casing in which is inserted an air cell to be inflated for imparting a flexible form to the fender calculated to absorb the pounding or chafing normally imparted to the sides of a boat when docked or lying side by side with other craft.

Another object of the invention resides in the novel manner of forming and closing the ends of the casing after the air cell has been inserted, whereby the air cell is entirely protected against injury or displacement either wholly or partially, yet being so arranged as to be conveniently inflated from time to time as may be required.

A further object of the invention resides in the application of looped end ropes through the end closures of the casing whereby the fender may be conveniently supported in position from a dock or the side of a craft or may serve as carrying handles.

A further and very important object of the invention resides in a heavy tubular canvas casing adapted to be positioned over the fender casing as a means to absorb wear and further as a means for supporting in looped form, a life line that passes entirely around the horizontal circumference of the fender, with its terminal ends spliced together and held against displacement at the ends of the fender by underlying the folded end of the fender casing.

Another distinct advantage in a fender of the above-named character is that the air cell may be formed of a conventional inner tube of vehicle tires by the addition of a second inflation valve arranged upon the outer periphery or tread portion of the tube whereby the tube may be distorted to a generally rectangular shape for insertion into the fender casing with the additional inflation valve projecting at one end for convenience.

Other obvious advantages of the invention will readily present themselves during the course of the following description, reference being had to the accompanying drawings wherein like characters of reference refer to like parts throughout the several views.

Referring to the drawings:

Figure 1 is a perspective view of the fender casing,

Figure 2 is a perspective view of the casing in assembled condition, illustrating the initial closure of the ends,

Figure 3 is a similar view of the completed fender,

Figure 4 is an end elevation of the fender shown in Figure 2,

Figure 5 is an end elevation of the fender as shown in Figure 3,

Figure 6 is a transverse section of the fender taken on line 6—6 of Figure 3,

2

Figure 7 is a perspective view of the tubular wear absorbing casing and,

Figure 8 is a view illustrating the fender air cell.

Referring specifically to the drawings, the numeral 5 designates a tubular, preferably heavy canvas casing, open at its ends. The casing will be formed of a sheet of canvas suitably united by stitching, not shown, and its ends will obviously be reinforced by hems and stitching, also not shown. Each open end adjacent its marginal edge is provided with four pairs of diametrically oppositely arranged relatively small grommets 6 and 7 and two pairs of relatively large grommets 8, spaced outwardly of the grommets 6. A tubular heavy canvas wear shield 9, see particularly Figure 7, is formed of a sheet of canvas united at 10, by stitching, with its ends open and suitably reinforced by stitching. Grommets 11 are longitudinally positioned in the tube 9, as shown and upon opposite diametrically disposed sides, for a dual purpose, to be described.

An air cell 12, see particularly Figure 8, is formed from a conventional vehicle tire inner tube. The cell 12 carries the conventional air inflation valve 13, as is customary. A second air inflation valve 14 is installed upon the tube 12, but in this instance, is mounted upon the tread portion of the tube at a point directly opposite the valve 13. The air cell thus provided utilizes an air container that can be purchased in the open market without the necessity of specially formed cells and their attendant costs and serves with equal success.

In the assembly of the device, the casing 5 and tube 9 having been previously formed and assembled, as in Figure 1 by merely slipping the tube 9 over the casing 5, the cell 12 is compressed to generally rectangular shape, as in dotted lines 40 in Figure 8 and is then inserted into the casing 5 and equidistantly spaced from the open ends thereof, with the valve 14 projecting at one end. The casings 5 and 9 assume a generally rectangular shape in cross-section after the cell is inserted. The terminal sides of the casing 5 are then folded inwardly, as in Figure 2 and laced together by lacings 15, passing through the grommets 7, with the valve 14 protruding therebetween. A life line 16, of rope or other material, is threaded through the grommets 11 of the tube 9, passing around the folded ends of the casing 5 and preferably under the lacings 15, with its terminal ends spliced together. The lacing of the line 16 through the grommets 11 form identical loops 17 upon both sides of the fender, serving as hand engaging loops when the device is used as a life preserver or life raft. After the line 16 has been installed, the top and bottom of the casing ends is folded inwardly, as in Figure 3 and lacings 18 passed through the grommets 6, with the terminal end of the valve 14 projecting therebetween. The air cell is then inflated through the projecting valve 14, to the desired pressure. A suspension or support rope 19 is

threaded through the large grommets 8 at both ends of the casing 5 and the terminal ends thereof spliced together. The rope 19 forms a pair of loops at each end of the fender that may be used to support the fender from a pier or the side of a boat or may be used as a handle to carry the fender from place to place. The fenders may be used as life preservers or when used in groups with the end ropes lashed together, forms an ideal raft and as such, may be arranged in pairs or various ways dependent upon the size of raft desired.

It will be apparent from the foregoing that a very novel and highly efficient fender has been provided. The device is simple in construction, readily and easily assembled, is strong, cheap to manufacture and the air cell and wear absorbing shield can be readily and easily replaced as becomes necessary. Since the tube 9 will absorb wear due to pounding and chafing when the device is used as a boat fender, it follows, that this tube, used as a protective shield for the casing 5, will require replacement from time to time and this can be accomplished with a minimum of effort and cost, since it is not permanently attached to the casing 5 and adds greatly to the overall life of the fender. The device, while primarily adapted as a boat fender, readily lends itself to various other activities, such as the life preserver, life raft, buoys and various water sports. The fender is extremely light in weight as compared with fenders heretofore used, since it depends upon the cushioning effect of the inflated air cell instead of the well known cork or kapok stuffings now in use, will not become hard and soggy and will remain pliant and free from noise due to the pounding of a boat thereagainst. The air pressure of the cell 12 is readily ascertainable by engaging a suitable pressure gauge to the valve 14 that normally protrudes outwardly of the folds of the casing for convenient inflation.

It is to be understood, that while a preferred example of the boat fender has been shown and described, it will be apparent that various changes in the shape, size and arrangement of parts may be resorted to as determined by the prior art and the scope of the subjoined claims.

Having described my invention, what I claim as new and desire to secure by Letters Patent is:

1. A combination boat fender and life raft that comprises a tubular casing formed of woven fabric and open at its ends, lacing grommets and rope connecting grommets fixed to each end of the casing, a wear shield of tubular form detachably engaged over the casing, grommets fixed to the wear shield upon opposite sides, an air cell formed of a vehicle tire tube compressed to oblong shape and inserted within the casing, the air cell provided with an inflation valve upon its tread surface to project from one end of the casing, the ends of the casing adapted to be folded inwardly and laced together through the lacing grommets, a life line extending entirely around the horizontal circumference of the casing and underlying the end folds, said line threaded through the grommets of the shield in looped form and supporting ropes threaded through the rope connecting grommets of the ends to provide looped portions.

2. A boat fender that comprises a tubular casing of heavy canvas open and reinforced at its ends, pairs of spaced grommets attached to the ends at diametrically opposite points for the reception of lacings, pairs of grommets of larger

diameter attached to the ends at diametrically opposite points for the reception of supporting ropes, a tubular wear shield of heavy canvas reinforced at its ends for detachable engagement over the casing and equidistantly spaced from the ends, longitudinally arranged spaced pairs of grommets attached to the shield upon opposite sides for the threaded reception of a life line, an air cell of circular form compressed to an oblong shape having rounded ends to be inserted into the casing and equidistantly spaced from the ends, an inflation valve formed in the cell to project at one end of the casing, the sides of the casing adapted to be folded inwardly and laced through certain of the first named grommets, the top and bottom of the casing adapted to be folded in and laced through certain of the first named grommets, a supporting rope threaded through the second named grommets and providing a pair of looped portions at both ends of the casing, the terminal ends of the ropes being spliced, a life line extending entirely around the horizontal circumference of the casing and underlying the folded portions of the casing, the life line being threaded through the grommets of the shield in a manner to form a pair of looped hand supports at either side of the fender, the terminal ends of the life line being spliced.

3. A pneumatic boat fender comprising a tubular casing of flexible woven fabric open at its ends, and an air cell for insertion within the casing to impart flexibility thereto, the ends of the casing being folded inwardly and laced to protect the air cell, the air cell formed from a vehicle inner tube having an inflation valve positioned upon its tread surface, the tube being compressed upon itself to oblong shape with rounded ends for insertion within the casing with the air valve positioned at one end of the casing and projecting outwardly, an elongated tubular wear shield of flexible woven fabric detachably positioned over the casing and equidistantly spaced from the ends of the casing, pairs of grommets fixed to the shield in horizontal arrangement and upon opposite sides, grommets fixed to the ends of the casing, the said air cell when inserted serving to impart a generally rectangular cross-section shape to the casing and shield, the side portions of the casing ends being folded inwardly and laced through certain of the grommets with the valve projecting therebetween, the top and bottom portions of the ends being folded inwardly and laced through certain of the grommets with the valve projecting therebetween, support ropes threaded through certain of the grommets of the casing ends to form a pair of loops at both ends of the fender, a life line passing entirely around the horizontal circumference of the fender and underlying the folded in end portions, the life line being threaded through the grommets of the shield to form a pair of identical loops upon both sides of the fender, the terminal ends of the ropes and line being spliced.
